(57) **CLAIM**

The ornamental design for a pair of tool handgrips, as shown and described.

DESCRIPTION

FIG. 1 is a perspective view of a pair of tool handgrips showing my new design, the upper and lower handgrips being mirror images of each other and shown by way of example as handgrips used for a wire cutter or snipper (dashed lines);

FIG. 2 is a perspective view of the upper handgrip shown in FIG. 1;

FIG. 3 is a top plan view of the handgrip shown in FIG. 1; FIG. 4 is a rear elevational view of the handgrip shown in FIGS. 2 and 3;

FIG. 5 is a bottom plan view of the handgrip shown in FIGS. 2-4;

FIG. 6 is a front elevational view of the handgrip shown in FIGS. 2-5;

FIG. 7 is a one end elevational view of the handgrip shown in FIGS. 2-6;

FIG. 8 is a cross-sectional view of the handgrip shown in FIG. 4, taken along the line 8—8; and,

FIG. 9 is the other end elevational view of the handgrip shown in FIGS. 2-8.

The broken lines shown on the drawings are for illustrative purposes only and form no part of the claimed design.
